INVENTOR
Arthur C. J. Roy.

UNITED STATES PATENT OFFICE.

ARTHUR C. J. ROY, OF PROVIDENCE, RHODE ISLAND.

WINDOW-SASH LOCK.

No. 926,899.

Specification of Letters Patent.

Patented July 6, 1909.

Application filed February 10, 1909. Serial No. 477,061.

To all whom it may concern:

Be it known that I, ARTHUR C. J. ROY, citizen of the United States, residing at the city of Providence, in the county of Providence and State of Rhode Island, have invented certain new and useful Improvements in Window-Sash Locks, of which the following is a specification, reference being had therein to the accompanying drawing.

10 My invention relates to locks or fasteners for window sashes, and has for its object to provide a fastener that will automatically lock the upper and lower window sashes together at their meeting rails each time 15 the window is closed, and retain them in a locked condition until manually released.

Means are also provided for retaining the locking plate when desired so that it will not automatically operate to lock the window 20 without first releasing the hook that retains it.

With these and other objects in view, the invention consists of certain novel features of construction, as will be more fully described and particularly pointed out in the 25 appended claims.

In the accompanying drawings: Figure 1—is a central sectional side elevation showing the two meeting rails in position and the locking plate removed from its catch on the 30 opposite window, in which position the window is free to be opened. Fig. 2—is a central sectional side elevation showing the lower portion of the window as in the act of being closed and in position to have the trip 35 lever actuated by contact with the catch to throw the latch and release the lock plate. Fig. 3—is a plan view showing the relative positions of the latch and lock plate and the retaining hook in position in said lock plate 40 to prevent the latter from being automatically operated. Fig. 4—is a front view of the lock plate, frame and its operating mechanism. Fig. 5—is a sectional plan view on line 5—5 of Fig. 4 showing the top of the frame 45 removed. Fig. 6—is a detail in perspective showing the trip lever. Fig. 7—is a detail in perspective showing the latch.

Referring to the drawings 1 is the meeting rail of the lower sash and 2 the meeting rail of the upper sash, in which panes of glass 3 and 4 are set respectively.

On the meeting rail 2 of the upper sash is mounted the catch member 5 which is provided with a slanting over-hanging nose 55 piece 6, said catch being secured to the rail

by means of screws 7—7 through its ears 8—8.

Mounted on the meeting rail 1 of the lower sash is the lower plate frame 9, which is provided with a top plate 10 on which is mounted the lock plate 11. This lock plate is formed with a tapering circular rib 12, see Fig. 3, which extends out from one side forming a manipulating handle 13, said rib coming substantially to a point at 14, whereby it is adapted to better enter the catch as it swings around into the same. This plate is mounted on the pivot pin 15, which pin is squared as at 16 through the plate and extends down through the top plate 10 of the frame. One end 17 of a coil spring extends through this pin and after taking several turns around the same the opposite end of said spring enters the top plate of the frame at 18 thereby providing means for automatically and quickly operating the lock plate to engage the catch as soon as permitted to do so by the withdrawing of its retaining latch. This retaining latch 19 is pivotally mounted near one end of the short shaft 20, the opposite end 21 of said latch being turned upward to extend through the hole 22 in the top of the frame and into the lock plate. The pivoted end of said latch is provided with an overhanging finger 23, by which the same is engaged and manipulated. This latch is normally held in its up or locked position by the tension of the coil spring 24 which is wound around said shaft 20, one end being arranged to engage the underside of said latch to press it upward. The trip lever 25 is also loosely mounted on this shaft 20 and is provided with a horizontally extending pin 26 which is adapted to project beneath the overhanging finger 23, said lever is also provided with an up-turned end 27 which is adapted to be engaged by the slanting edge of the nose on the catch, in the manner illustrated in Fig. 2, to tip back said trip lever, causing its pin 26 to engage the finger 23 on the latch to withdraw the up-turned end of the latter from the lock plate, whereby the operating spring of the lock plate will cause said plate to rotate, and as soon as the window is closed into position this lock plate will follow around beneath the catch on the opposite rail securely locking the two sashes together.

This trip lever is normally held up in position and in contact with the latch by a slight spring 28. This trip lever is arranged so that it may be tipped 105

105

110

back out of the way beneath the lock frame to allow the upper rail of the upper sash to pass the upper rail of the lower sash when the top rail of one window sash is required to pass 5 the top rail of the other sash, which is sometimes found necessary in cleaning said windows.

It is found in practice in some cases such as in cleaning the windows, etc., of advantage 10 to retain the locking plate in its released position so that it will not be automatically operated when the windows are manipulated. To accomplish this I have provided a hook member 29 which is pivoted at 15 30 in the lock plate frame. This hook member is provided with a downwardly turned end 31 which is adapted to engage a slot 32 formed to receive it in the locking plate. This hook is also provided with a handle 33 20 by which it may be manipulated.

My improved lock is simple in construction, positive in its action and may be automatically operated to positively lock the window each time the window is closed.

25 Having thus described my invention, what I claim as new and desire to secure by Letters Patent, is:

1. A sash lock comprising a frame, a spring actuated lock plate rotatably mounted in said frame, a latch for retaining said plate, a catch on the opposite window sash, and a trip lever adapted to be actuated by said catch whereby said latch is operated to release said lock plate to move into engagement with said catch when the windows are closed.

2. A sash lock comprising a frame, a spring actuated lock plate rotatably mounted in said frame, a pivotally hung latch for retaining said plate, a catch on the opposite window sash, and a pivoted trip lever for controlling said latch, said trip adapted to be actuated by said catch whereby said latch is operated to release said lock plate to move into engagement with said catch when the windows are closed.

3. A sash lock comprising a frame, a spring actuated lock plate rotatably mounted in said frame, a spring pressed latch for retaining said plate and a trip lever for controlling said latch, a shaft in said frame on which both said latch and lever are loosely mounted, and means on the opposite window sash for receiving the lock plate and also for 55 engaging and operating said trip to release said lock plate to move into engagement with said receiving means.

4. A sash lock comprising a frame, a spring actuated lock plate rotatably mounted in said frame, a spring pressed latch for retaining said plate, a trip lever for controlling said latch, a shaft in said frame on which both said latch and lever are loosely mounted, a catch on the opposite window sash, the end of said trip lever being turned up to be 60 engaged and operated by said catch to release the lock plate to move into engagement with said catch.

5. A sash lock comprising a frame, a spring actuated lock plate rotatably mounted in said frame, a spring pressed latch for retaining said plate, a trip lever provided with a laterally extending pin for engaging said latch, a shaft in said frame on which both said latch and lever are loosely mounted, a catch on the opposite window sash, the end of said trip lever being turned up to be 70 engaged and operated by said catch to release the lock plate to move into engagement with said catch.

6. A sash lock comprising a frame, a spring actuated lock plate rotatably mounted in said frame, a latch for retaining said plate, a catch on the opposite window sash, a trip lever adapted to be actuated by said catch whereby said latch is operated to release said lock plate to move into engagement with said catch when the windows are closed, and a manually operated hook adapted to be moved into engagement with the 80 lock plate to prevent the same from being automatically operated when the window is brought to its closed position.

7. A sash lock comprising a frame, a spring actuated lock plate rotatably mounted in said frame, a spring pressed latch for retaining said plate, a trip lever for controlling said latch, a shaft in said frame on which both said latch and lever are loosely mounted, a catch on the opposite window sash, the end of said trip lever being turned up to be 90 engaged and operated by said catch to release the lock plate to move into engagement with said catch, and a manually operated hook adapted to be moved into engagement with the lock plate to prevent the same from being automatically operated when the window is brought to its closed position.

In testimony whereof I affix my signature in presence of two witnesses.

ARTHUR C. J. ROY.
